303

302

UNITED STATES PATENT OFFICE.

EDWARD C. ALBREE, OF SWAMPSCOTT, MASSACHUSETTS.

ACCOUNTING SYSTEM.

No. 902,543.

Specification of Letters Patent.

Patented Nov. 3, 1908.

Application filed February 28, 1906. Serial No. 303,371.

To all whom it may concern:

Be it known that I, EDWARD C. ALBREE, a citizen of the United States, residing at Swampscott, county of Essex, State of Massachusetts, have invented a certain new and useful Improvement in Accounting Systems, of which the following is a specification, reference being had therein to the accompanying drawings.

10 In accounting systems of the kind shown and described in my application, Serial No. 303,418, filed Feb. 28, 1906, to which reference may be had for further particulars, it is found convenient to provide the cards with 15 certain arbitrary marks at predetermined points to assist in the superposition of the cards and in recording upon them the desired information. These arbitrary marks add greatly to the efficiency of the system 20 because they save a great amount of time, and they also assist the user of the cards to perform certain problems or operations which would not be readily performable if the cards were not provided with these marks. 25 Cards having thereon certain of these arbitrary marks may also be used to determine the value of the spaces intervening between any two punch marks upon another card and for certain other purposes. My present 30 invention also includes the method of recording accounts by means of certain steps performed with and upon the cards to be described herein.

I will describe my invention as embodied 35 in cards such as may be used in accounting systems of the kind described in my previous application because that is the form in which I have put my invention into actual practice, but it is obvious that many modifications may be made without departing from 40 the spirit of the invention.

The invention will be fully understood from the following description taken in connection with the accompanying drawings 45 and the novel features thereof are pointed out and clearly defined in the claims at the close of the specifications.

In the drawings,—Figure 1 is a view of a 50 job card provided with "starting dots." Fig. 2 is a view of a workman's card, Fig. 3 shows the card H (see Fig. 2,) superposed upon the card A (see Fig. 1,) with the lower edge of the card A in registration with the space containing the lower starting dot. 55 Fig. 4, shows the card H (see Fig. 2,) superposed upon the card A' with the punch-

mark K in registration with the upper starting dot G. Fig. 5, is a view of a workman's time card having several records punched thereon. Fig. 6, is a view of a reckoning 60 card. Fig. 7, shows this card M (see Fig. 5,) superposed upon the card Q (see Fig. 6,) to determine the value of the spaces between the beginning of the card and the punch mark N. Fig. 8, shows the same cards in position to determine the value of the spaces between the punch mark N and the punch mark O. Fig. 9, shows the same cards again superposed to determine the value of the spaces intervening between the punch mark 70 O and the punch mark P. Fig. 10, shows the "ready reckoner" or reckoning card provided with one reckoning mark and two scales. Fig. 11, shows a job card having records of work recorded thereon. Fig. 12, 75 shows a workman's card also having records of work recorded thereon. Fig. 13, shows the card 28 (see Fig. 12,) superposed upon the card 26 (see Fig. 12,) with the punch mark 29 in registration with the punch mark 80 27. Fig. 14, shows the same cards superposed with the punch mark 302 and pencil mark 301 in proper relative positions. Fig. 15, shows another job card with a record of work thereon. Fig. 16, shows the card 50 85 (see Fig. 18,) superposed upon the card 32 (see Fig. 15) with the punch mark 52 and 33 in registration. Fig. 17, shows the same card superposed with the punch mark 54 in registration with the pencil mark 34. Fig. 18, shows another workman's card having a 90 record of work recorded thereon.

In my application previously referred to, there is described a job card upon which the record of work performed by various workmen is kept. Such a card A is shown in Fig. 1, and as there shown may be divided into unit spaces B of equal size arranged in columns and provided with total figures C which are placed upon the cards at convenient intervals. The columns of unit spaces on this card and on the other cards comprising the system are of equal height. Each of the unit spaces has a value of one cent, and the total figures C are applied to every fifth space as 95 shown in the drawings. An additional space is left at the bottom of each job card as shown at D, and a margin E equal in width to one of the spaces B is left on the right side of the card.

Below the lowest space in the right hand column, I place a dot or other convenient dis-

tinguishing mark F, which for convenience I call the "lower starting dot", and near the upper right hand corner of the card in the margin E and at a distance below the top line of the unit spaces equal to one of the unit spaces B, I place what I term the "upper starting dot" G. It will at once be seen that fifty unit spaces intervene between the upper and the lower starting dots. This arrangement I believe at the present time to be necessary. Of course it is to be understood that if the cards were made with one hundred spaces in a column as might be the case, the distance between the starting dots would be correspondingly increased.

Referring now to Fig. 2, there is there shown a workman's card H similar to those described in my previous application heretofore referred to. This card is divided into 20 unit spaces of the same size as the unit spaces on the card Fig. 1, previously referred to, but these unit spaces begin at the very bottom of the card and no margin on the right hand side is left as is the case in connection with 25 the job or record card (see Fig. 1). Total figures C' are provided in the same manner as on the card of Fig. 1, and in addition thereto there are hour numerals 1 to indicate the day and hour of the week, placed upon the card 30 in accordance with the rate of wages which the workman using the card received, as described in my previous application.

The workman's card, or primary or guide card as it is variously called, which has just 35 been described, and the job or record card such as is shown in Fig. 1, are punched simultaneously, the guide card being superposed upon the record card. Thus, if the workman completes the job represented by the 40 card of Fig. 1 at five o'clock on Tuesday, having worked on the job from seven o'clock on Monday, he takes the two cards to the inspector, who superimposes the workman's card H upon the job card A with the lower 45 right hand corner of the workman's card just above the lower starting dot F, as shown in Fig. 3, and punches them as shown at K at the hour when they are brought to him, namely, five o'clock on Tuesday at the point 50 indicated by the hour numeral E'. When the workman next goes to the inspector, having completed a job as for instance at three o'clock on Thursday, the inspector places the job card A' and the workman's card H together with the hole K registering with the 55 upper starting dot G (see Fig. 4) and punches both cards simultaneously at the proper hour numeral which is in this case U³ as indicated at L, thus adding \$.90 to the wages already 60 earned by the workman and making simultaneous records on both cards.

It will be seen from the foregoing that sometimes the upper starting dot G is used and sometimes the lower starting dot F, and 65 that these dots enable the inspector to place

the two cards together in the proper position for punching with the least possible delay. The lower starting dot F is employed when the hour numeral to be punched lies above the last previous punch mark, while the upper starting dot is used when this hour numeral lies below the last previous punch mark.

In the use of my improved accounting system it is sometimes desirable to add simultaneously a like amount to the amounts already recorded on the primary or workman's time card and on the secondary or job card. This problem is one of some difficulty and I have accordingly provided special means for 80 simplifying the operation.

In Fig. 11 I have illustrated a job or secondary card 26 which is divided into the usual unit spaces and is punched at 27, thus showing that \$.15 worth of work has been 85 done up to this point. In Fig. 12 there is shown a primary or workman's card 28 for use by a workman earning \$.05 an hour. This card is divided into unit spaces as is usual and is punched at 29 at two o'clock on 90 Monday to show that \$.30 worth of labor has already been recorded on this card. Suppose the workman to whom the primary card 28 belongs works until Wednesday at nine o'clock. It will be seen that if the card 28 is 95 superposed upon the card 26, with the punch marks at 27 and 29 in registration with each other, the point indicated by nine o'clock Wednesday on the card 28 will fall below the edge of the card 26 so that if the card 28 should be punched at nine o'clock the card 26 will not be punched at all. My invention obviates this difficulty in the following manner. I first punch out of the workman's card 28 the space opposite the top row of the hour 105 numerals and in the column next adjacent the used spaces of the card and at the left thereof as seen at 30 in Fig. 12. I then place the cards together with the punch marks 27 and 29 in registration with each other (see 110 Fig. 13) and mark with a pen or pencil through upon the card which is underneath the point where punch mark 30 just described falls as indicated at 301 (see Fig. 11). This mark may be made with different colored pencils or inks if convenient to distinguish or identify the mark. I then superpose the cards again as shown in Fig. 14 with the lower edge of the card 28 against the upper edge of the space occupied by the mark 115 301 which was made as just described, the card 28 being placed with the column of spaces next to the left of the punch mark 30 in registration with the column of spaces of the card 26 in which appears the pencil mark 120 301 previously referred to. In practice it 125 may be found convenient to provide the cards with two special marks one being located as the punch mark 30 is located, and the other occupying the bottom space of the 130

column next to the left of that in which the punch mark 30 is placed. Such a mark is indicated at 302 in Fig. 14 and serves to assist in placing the cards in proper position 5 with relation to each other. Both cards are then punched at nine o'clock as indicated at 31 in Fig. 14. This operation will now be seen to have added to both cards the value of the units spaces lying between 29 on card 10 28 (Fig. 12) and 31, see Figs. 12 and 14. This is the operation or mode of procedure which is employed when the number to be punched on the primary card falls below the bottom edge of the job card.

15 In certain cases the number to be punched upon the primary card falls above the top edge of the job card, and in that case the following is the mode of procedure. Let it be supposed that a job card 32, see Fig. 15, has 20 been punched at 33 indicating a charge of \$ .45 to that job card, and that it is desired to add \$1.60 to a workman's or primary card 50 (see Fig. 18) and upon which has been punched at 52 time to the value of \$.30, or 25 in other words that the workman to whom the card of Fig. 18 belongs works from two o'clock on Monday until four o'clock Thursday on the job of the card of Fig. 15. When the cards are superposed with the two punch 30 marks 52 and 33 in registration, (see Fig. 16,) the point indicated by four o'clock Thursday will be seen to fall above the upper edge of card 32. In this case I mark with the pen or pencil the unit space lying next below the 35 mark 302 at the bottom edge of the card 50 as shown at 34 and then punch the unit space in the column next before the column at the bottom of which the mark 302 previously referred to is located, said unit space being 40 the one next adjacent and to the left of the hour numeral 56. This punch mark is designated 54. The cards are then placed together with the punch mark 54 over the pencil mark 34 so that the pencil mark may be 45 seen through the punch mark and the two cards are punched together at the time desired, namely, four o'clock on Thursday as indicated at 341. This last operation is to be seen by reference to Fig. 17. The result 50 of this operation is the same as that previously described. It is not absolutely necessary to provide the cards with any special marks to assist in performing this operation, because the upper unit space of the proper 55 column may be employed and the bottom edge of the card forms a convenient guide in the placing of the two cards together, but in practice I find as previously stated that special marks placed as specified are convenient.

Having described the general construction and operation of what I term "dot cards" I will now describe the manner in which the same dot cards may be employed for determining the value or distance of the spaces

between any two punch marks on other cards belonging to the same system.

In Fig. 5 there is shown a workman's time card M which is punched at N on Monday at two o'clock, at O on Wednesday at three o'clock, and at P on Friday at eight o'clock. To determine the value of the spaces from the beginning of the card to the punch mark N, the card M of Fig. 5 is applied to a reckoning card Q, see Fig. 6, which is like the job cards previously described, such for instance as are shown in Fig. 1, in all respects except that the said cards are provided with rectangular marks of about the size and shape of one of the spaces B located in the spaces next above the starting dots F and G. Of course it is to be understood that marks of other forms might be employed if preferred. I have, however, described rectangular marks because that is the form which I have happened to use in actual practice. For convenience I call these marks "reckoning marks", and have given them the designating characters R and S. To determine the value of the spaces on the card M of Fig. 5, as far as the punch mark N, the card M is applied to the reckoning card, which I have just described, with its lowermost edge against the reckoning mark S and the total figure which lies underneath the punch mark N and is visible through it, is then read. In this case, it will be seen to be \$.30. It will be seen that where there are several punch marks on the cards, the values of the spaces intervening between the punch mark which is in registration with the reckoning mark and the succeeding punch marks are all visible through the respective punch marks, this information being afforded by the total figures.

To determine the distance between the punch mark N and the succeeding one O, the card M, see Fig. 5 is placed upon the reckoning card Q with the punch mark N in registration with the reckoning mark S and the total figure on the card Q which shows through the punch mark O is read. This operation is shown in Fig. 8. This total figure is \$1.05, which shows that the value of the intermediate space between the punch mark N and the punch mark O is \$1.05.

To determine the value or distance between the punch mark O and the punch mark P, the card M is placed upon the reckoning card Q with the punch mark O registering with the reckoning mark R and the total figure on the reckoning card Q is read through the punch mark P. This operation is shown in Fig. 9. In this case the total figure is \$.70.

It will thus be seen that, as in the case of the starting dots previously described, when the final punch mark lies below the initial punch mark of the two marks between which it is desired to determine the value of the

spaces, the initial punch mark is placed upon the upper reckoning mark R, whereas if the final punch mark lies above the initial punch mark the lower reckoning mark is employed. 5 The reason why the guide dots F and G cannot conveniently be employed for this purpose is the fact that an additional space D has been left at the bottom of the job cards and reckoning cards as previously described, for 10 the purpose of permitting the total figures to be placed in such a position that the spaces next below may be punched without obliterating the total figures pertaining thereto. But both the starting dots and 15 reckoning marks bear the same relation to the lines and figures forming the divisions or scale on the card except for this change of one space to prevent obliteration. It will also be noticed that the upper reckoning 20 mark R and starting dot G are placed in the margin E of the card, this being the only place, so far as I am now aware, where these dots may be placed and bear the proper relation to the spaces B comprising the body of 25 the card.

Where it is necessary to determine the value or distance between the various punch marks on a large number of cards, I find it convenient to provide a special reckoning 30 card T, of the form shown in Fig. 10, which is provided with only one reckoning dot located at U, and with two scales V and W, each of which are like the spaces or scale provided on the job card A and reckoning 35 card Q previously described, and are furnished with total figures in the same manner. The upper scale V bears the same relation to the reckoning mark U as the scale on the card Q bears to the lower reckoning mark S, 40 while the lower scale W on the card T bears the same relation as the scale on the reckoning card Q bears to the upper reckoning mark R. In other words, the reckoning card Q shown in Fig. 9, and the reckoning 45 card T, shown in Fig. 11, are like each other except that the card Q is provided with one scale and two reckoning marks whereas the card T is provided with two scales and one reckoning mark.

50 What I claim is:

1. The improved card for an accounting system provided with outlined spaces of uniform size arranged in columns of equal height, a margin on one side thereof, and a 55 mark in the said margin adjacent the top

space of that column of spaces which is next the said margin.

2. The improved card for an accounting system provided with outlined spaces of uniform size arranged in columns of equal height, a margin on one side thereof, a mark in the said margin adjacent the top space of that column of spaces which is next the said margin, and a second mark in the bottom space of the said column of spaces. 60 65

3. The improved card for an accounting system, provided with outlined spaces of uniform size arranged in columns of equal height, a margin on one side thereof of a width equal to the width of one of the said 70 spaces, and a mark in the said margin adjacent the top space of that column of spaces which is next the said margin. 75

4. The improved card for an accounting system provided with progressively numbered outlined spaces of uniform size arranged in columns of equal height, a margin on one side thereof, and a mark adjacent the next to the top space of that column of spaces which is next to the said margin. 80 85

5. The improved card for an accounting system provided with outlined spaces of uniform size arranged in columns of equal height, a margin on two adjacent sides thereof, a mark in the said margin adjacent the top space of that column of spaces which is next the said margin, a second mark in the bottom space of the said column of spaces, and two other marks located immediately 90 95 below the two first mentioned marks. 100

6. The improved card for an accounting system provided with outlined spaces of uniform size arranged in columns of equal height, a margin on two adjacent sides thereof, a mark in the said margin adjacent the top space of that column of spaces which is next the said margin, a second mark in the bottom space of the said column of spaces, and two other marks located immediately below the two first mentioned marks, said two last mentioned marks being different in shape from said two first mentioned marks to avoid confusion.

In testimony whereof I affix my signature, in presence of two witnesses.

EDWARD C. ALBREE.
